SURGICAL HEADLIGHT

Richard E. Feinbloom, New York, N.Y., assignor to
Designs for Vision, Inc., New York, N.Y.

Filed Jan. 15, 1973, Ser. No. 323,704

Term of patent 14 years

Int. Cl. D26—99

U.S. Cl. D48—20 H

FIG. 1 is a perspective view of a surgical headlight of my new and original design;

FIG. 2 is a side view of the surgical headlight;

FIG. 3 is a top plan view of the surgical headlight; and

FIG. 4 is a rear view of the surgical headlight with a portion of the headstrap being broken away for purposes of disclosure.

FIG. 5 is a fragmentary rear view of that portion of the strap omitted in FIG. 4. The remainder of the headlight being omitted for convenience of illustration.

The surgical headlight is shaded with cross-hatching to indicate contrast. It is understood that the cross-hatching is uniformly continuous over the elements indicated.

I claim:

The ornamental design for a surgical headlight, as shown and described.
